UNITED STATES PATENT OFFICE.

LAWRENCE DAVISON, OF EDMON, PENNSYLVANIA, ASSIGNEE OF ONE-FOURTH TO
WILLIAM GOUDY AND ONE-FOURTH TO D. H. SLONAKER, BOTH OF AVONMORE,
PENNSYLVANIA.

GUARD BRACKET FOR ELECTRIC WIRES.

Application filed August 20, 1927. Serial No. 214,252.

My invention relates to guard brackets for electric wiring, and more particularly to brackets for supporting guard rails or boards in proximity to trolley wires.

5 One object of my invention is to provide a bracket that is readily applicable to wire supports of various styles and sizes.

Another object of my invention is to provide a bracket that is readily adjustable in 10 directions vertically and horizontally transverse to a wire or trolley conductor with which it is associated.

Still another object of my invention is to simplify and improve generally the structure 15 and arrangement of guard brackets.

Some of the forms which my invention may take are shown in the accompanying drawing, wherein Figure 1 is a sectional view of a supporting structure showing my 20 bracket in place, and taken on the line I—I of Fig. 2; Fig. 2 is a view taken on the line II—II of Fig. 1; Fig. 3 is a modification of the structure of Fig. 1, and Fig. 4 is a plan view of the yoke device of Fig. 3.

25 While my invention is applicable to use in various other relations, I have shown it as employed in association with a trolley wire 3 that is supported by a clamp 4 of any well-known form, which is in turn supported by a hanger 5 that is connected to a timber 6, placed against a supporting surface 7.

The principal parts of the bracket consist of two collar members 8 and 9 that support 30 bars 10 and 11 respectively of angular form, to which are connected channel members 12 and 13. These parts may be of sheet metal or other suitable material.

A pair of links 14 are pivotally connected 40 to the collar 8 and the adjacent end of the collar 9 lies between these links, the collar 9 being provided with a clamping bolt 14^a that extends through the slots in the links 14 and affording a means for adjustment of the 45 collars longitudinally of the links, to enable the collars to be tightly fitted to hangers of various dimensions.

At their other ends, the collars 8 and 9 are detachably connected by means of an 50 eye-bolt 15 that is pivotally connected to the collar 8 and can therefore be swung into and out of position in a slot that is provided in the adjacent end of the collar 9, a wing nut 16 being provided to clamp the

collars 8 and 9 securely in position upon the 55 hanger 5.

The angle bars 10 and 11 are slotted at their upper ends, so that they may be adjusted laterally of the wire 3, the bars 10 and 11 being held in adjusted position by 60 means of bolts 17 that extend through the collars 8 and 9 and are provided with wing nuts.

The yokes 12 and 13 are connected to the 65 bars 10 and 11 by means of bolts 18, a series of vertically-spaced holes being provided in the bars and the yokes, so that the yokes can be adjusted to desired vertical heights. The yokes 12 and 13 serve as supports for 70 guard members, such as boards 19, it being understood that these boards are of suitable lengths and that they are supported at suitable intervals by means of brackets, as just described. The yokes 12 and 13 are pivotally supported on the bolts 18, so that 75 they can swivel to allow the guard boards to follow a desired inclination, depending upon the grades or slopes present where they are employed.

Referring to Figs. 3 and 4, I show a modified form of bracket as employed in connection with an expansion bolt structure 20 that may be supported in the roof 21 of a mine in the usual manner. The bracket structure includes a plate 22 that corresponds to the 80 collar members 8 and 9 and is slotted to permit it to be slid into position as shown in Fig. 3, the expansion bolt being set to provide sufficient clearance beneath the surface of the mine roof, or being unscrewed 90 to provide such clearance. The collar plate 22 supports angle plates 10^a and 11^a, that correspond to the plates 10 and 11 of Fig. 1, and these plates in turn support yokes 12^a and 13^a, the bracket parts, except for the 95 plate 22, being adjustable as in the case of the corresponding members of Figs. 1 and 2.

Not only does the arrangement above described permit of the convenient and secure application of the bracket to wire hangers of various styles and sizes, but the boards 19 may be conveniently located at various vertical positions with respect to the trolley wire, and they can be adjusted horizontally in directions transverse to the wire. This 100 latter feature is particularly useful where the trolley wire extends around the curve, since if no provision were made for lateral 105

adjustment of the guard boards, they would at some places lie so close to the wire as to interfere with the operation of a trolley, and at other points would be disposed so far away from the wire as to afford inadequate protection.

I claim as my invention:—

1. A guard bracket comprising a pair of collar members arranged to embrace a hanger, means for pivotally connecting said members at one end for movement about an axis perpendicular to the plane of the collar members, means for adjusting the point of pivotal connection, in a direction tangentially of the said members, means for detachably connecting the other ends of said collar members, and a guard rail support carried by each of the collar members.

2. A guard bracket comprising collar members arranged to embrace a hanger, means for connecting adjacent ends of said members at various points tangentially thereof, and means on said collars for supporting guard rails, the said means being adjustable radially of the collar members.

3. A guard bracket comprising collar members arranged to embrace a hanger, means for connecting adjacent ends of said members at various points tangentially thereof, and means on said collars for supporting guard rails, the said means being adjustable axially of said collar members.

4. A guard bracket comprising collar members arranged to embrace a hanger, means for connecting adjacent ends of said members at various points tangentially thereof, and means on said collars for supporting guard rails, the said means being adjustable radially and axially of said collar members.

5. A guard bracket comprising a collar device arranged to embrace a hanger, a pair of angular supports carried by said device and each having a vertical extension, and a guard rail support connected to each of said vertical extensions, the said angular support

and guard rail supports being adjustable relative to each other and relative to the collar device.

6. A guard bracket comprising a collar device arranged to embrace a hanger, a pair of angular supports carried by said device and each having a vertical extension, and a guard rail support connected to each of said vertical extensions, the angular supports being adjustable in a horizontal plane.

7. A guard bracket comprising a pair of collar members arranged to embrace a hanger, an angular support carried by each of said members and having a vertical extension, and a guard rail support connected to each of said vertical extensions, the angular support being adjustable in a horizontal plane, and the guard rail supports being adjustable vertically.

8. A guard bracket comprising a collar device arranged to embrace a hanger, a pair of angle members carried by the collar device, and each having one of its flanges depending therefrom, and a support of U-like form connected to each of said angle members for supporting guard rails, the said supports being adjustable relative to the angle members.

9. A guard bracket comprising a collar device, a guard rail support extending below and in a plane at right angles to the plane of said device, and means for pivotally connecting the said support to said collar device.

10. A guard bracket comprising a collar device, a guard rail support extending below and in a plane at right angles to the plane of said device, and means for pivotally connecting the said support to said collar device on an axis disposed parallel to the first-named plane and at right angles to the second-named plane.

In testimony whereof I, the said LAWRENCE DAVISON, have hereunto set my hand.

LAWRENCE DAVISON.
